UNITED STATES PATENT OFFICE.

FRANK L. LARAYA, OF WORCESTER, MASSACHUSETTS, ASSIGNOR TO CULVER STEARNS MANUFACTURING COMPANY, OF WORCESTER, MASSACHUSETTS, A CORPORATION OF MASSACHUSETTS.

SWITCH SOCKET.

Application filed June 30, 1926. Serial No. 119,720.

This invention relates to a switch socket for a lamp or other electrical connection. The principal objects of the invention are to provide a simple and inexpensive switch 5 socket which can be turned on and off by oscillation of a projecting handle and in which the parts are made of comparatively few pieces and only two pieces of insulation in the outer part.

10 Other objects and advantages of the invention will appear hereinafter.

Reference is to be had to the accompanying drawings in which

Fig. 1 is a side view of a switch socket 15 for a lamp constructed in accordance with this invention;

Fig. 2 is an enlarged central sectional longitudinal view of the same;

Fig. 3 is a sectional view of the outer 20 member, on the line 3—3 of Fig. 2;

Fig. 4 is a longitudinal central sectional view of the same with the outer electrical connection removed;

Fig. 5 is an end view thereof from the 25 left of Fig. 4 looking into the outer shell;

Fig. 6 is a central longitudinal sectional view of the internal cup;

Fig. 7 is an end view of the same, and

Fig. 8 is a diametrical sectional view of 30 the socket.

This switch socket comprises two main parts, an outer shell 10 and the inner cup 11. The outer shell is formed of sheet metal with a drawn in end 12 which constitutes 35 the bottom or end of the device and is provided with an opening extending through it and with a couple of opposite notches 13 on the end extending radially. It is provided with the usual bayonet slots 14 and 40 with a circumferential slot 15 for a purpose to be described.

The shell 10 is mechanically connected 45 with a cable 16 by a conducting member 17 having a shoulder 18 and a head 19 separated from each other. Between the two shoulders thus formed are two insulating washers 20 and 21 of vulcanized fibre or the like. These are separated at their edges and between them comes the end wall 12 which 50 has been described. It will be seen that on account of this construction the electric line is insulated from the shell 10. The inner insulating member 21 is of stiff material and is provided with a pair of radial slots 22 55 through it near its edge.

Inside the shell 10 is located a sheet metal cup 11. This has a radial operating handle 25 extending through the slot 15 for swinging it. This slot is wider than the thickness of the handle. The cup is provided with a central plunger 26 pressed by a spring 24 operating in connection with the lamp 27 in the usual well known manner. The plunger is mounted in a metallic member 28 fixed to an insulating disc 29 which extends across 60 the bottom of the cup 11. The sheet metal of the cup is bent inwardly at 30 in one or more places to hold this disc 29 in place which engages the flange 31 at the bottom of the cup. This flange is open and, with the 70 disc 29, furnishes a wide insulation against the contact of the metallic member 28 with the other metallic parts. On this flange 31 are two opposite radial projections 33 adapted upon the turning of the cup to pass 75 into the slots 22.

I have shown a one terminal lamp for engaging the plunger 26 and forcing it back into a position in which it is held by the spring pressure in the bayonet slots as usual. 80 The two insulating discs 29 and 21 are of sufficient strength to hold in place the metallic parts fastened thereto.

It will be understood that in the position shown in Fig. 2 the projections 33 are not 85 in the slots 22. Consequently the conducting metallic member 28 is held away from the flange 19. When the handle 25 is turned to bring the projection 33 into the slots 22 the member 28 will be allowed to come down 90 into contact with the end flange 19 on the conductor 17 which carries the cable 16. Therefore the circuit is completed through these parts to the lamp and out again 95 through the metallic parts thereof to the shell 10 which is grounded. The shell 10 is insulated by the three insulating discs from the central conducting line. When the handle 25 is turned again it brings the projections 33 up on the top of the disc 21 and 100 separates the members 28 and 19 so as to shut off the current. This is the reason for making the slot 15 wider than the handle 25.

Although I have illustrated and described only a single form of the invention I am 105 aware of the fact that modifications can be made therein by any person skilled in the art without departing from the scope of the invention as expressed in the claims. Therefore, I do not wish to be limited to all the 110

details of construction herein shown and described, but what I do claim is:—

1. In a switch socket, the combination of a shell of metal adapted to be connected with one side of a circuit and having a bayonet slot for the reception of the metallic base of a lamp for connecting the lamp to the circuit, a metallic cup in the shell, a spring plunger carried by the metallic cup 10 constantly engaging the end of the lamp base and making the other connection at that point, means for insulating the spring plunger from the cup, a conductor connected with an electric cable located in line with the spring plunger, projecting into the base of the shell, and insulated from the shell and cup, said cup having a passage through it at the base through which the base of the spring plunger projects, means 20 for turning the cup, and means on the cup for moving it outwardly so that the base of the spring plunger and the conductor will be out of contact when the cup is turned into one position and in contact when turned to another position.
2. In a switch socket, the combination with a metallic shell having an open end, a conductor centered in said end for connecting it to the circuit on one side, the shell 30 acting as the other terminal, and an insulating disc insulating the shell from the conductor, of a cup within the shell adapted to be turned to two positions, said cup having projections on the base for engaging said insulating disc, said disc having depressions in it for receiving said projections and allowing the cup to move longitudinally when turned to a certain position, and a spring plunger in the cup and insulated 40 from it, and having a base movable with the cup, whereby when the cup is turned it will bring the base of the spring plunger into and out of contact with the end of said conductor.
3. In a switch socket, the combination with a metallic shell having an open end, of a conductor centered in said end for connecting the current on one side, the shell

acting as the other terminal, two insulating discs supporting said conductor and supported by the shell and insulating the shell from the conductor, a cup within the shell adapted to be turned to two positions, said cup having integral metallic projections on the base for engaging one of said insulating discs, said disc having depressions in it for receiving said projections and allowing the cup to move longitudinally, said cup having an insulating disc therein and a spring plunger supported by the last-named disc 50 and insulated thereby from the cup and shell and projecting through the disc whereby when the cup moves longitudinally it will bring the base of the spring plunger into and out of contact with the end of the 55 conductor.

4. As an article of manufacture, a switch member comprising a cylindrical shell for receiving a lamp base, a conductor extending into the end of the shell for holding an electric conducting cable, said shell having an insulating disc inside receiving the end of said electric conductor and keeping it insulated from the shell, said disc having openings therethrough oppositely arranged, 70 an inner cup having projections cooperating with said openings for permitting the movement of the cup, and a second insulating disc outside the end of the shell, said conducting member being held by the two discs.

5. As an article of manufacture, an electric switch comprising a metallic shell and a cup member adapted to fit in the metallic shell and having a handle projecting therefrom by which it may be turned to two positions, a spring plunger in the center of the cup having a base projecting through to the lower side, said cup having two opposite integral projections, and an insulating disc having depressions for receiving said projections so that when the cup is turned to two limiting positions these projections will control its position.

In testimony whereof I have hereunto affixed my signature.

FRANK L. LARAVA.
